UNITED STATES PATENT OFFICE

171,972

APPAREL ORNAMENT

John B. Freysinger, Newington, Conn., assignor to Keyston Brothers, San Francisco, Calif., a corporation of California

Application January 4, 1954, Serial No. 28,357

Term of patent 3½ years

(Cl. D17—2)

To all whom it may concern:

Be it known that I, John B. Freysinger, a citizen of the United States and a resident of Newington, in the county of Hartford, State of Connecticut, have invented a new, original, and ornamental Design for an Apparel Ornament, of which the following is a specification, reference being had to the accompanying drawing forming part hereof.

In the accompanying drawing:

I claim:

The ornamental design for an apparel ornament, as shown.
